UNITED STATES PATENT OFFICE.

OMAR E. CLARK, OF DENVER, COLORADO, ASSIGNOR TO THE DENVER ROCK DRILL MANUFACTURING COMPANY, OF DENVER, COLORADO, A CORPORATION OF DELAWARE.

FLUID-PRESSURE-OPERATING MECHANISM.

1,183,275.

Specification of Letters Patent. Patented May 16, 1916.

Application filed April 24, 1915. Serial No. 23,636.

To all whom it may concern:

Be it known that I, OMAR E. CLARK, a citizen of the United States, residing at Denver, in the county of Denver and State 5 of Colorado, have invented new and useful Improvements in Fluid-Pressure-Operating Mechanism, of which the following is a specification.

The present invention relates more particularly to means for lubricating pneumatic tools and the like, and more especially those employed in rock drills. In that type of rock drills wherein automatic means is provided for effecting the rotation of the 15 drill bit, considerable difficulty has been experienced in lubricating the rotating mechanism which as is well known is ordinarily placed at the front end of the cylinder member.

20 One of the objects of the present invention is to provide simple mechanism of an automatic character that depends for operation on the pulsation or rise and fall in the fluid pressure due to the actuation of the 25 motor, and furthermore results in the vaporization of the lubricant, and its even distribution to all the working parts and particularly the rotating mechanism.

One embodiment of the invention is illustrated in the accompanying drawings, 10 wherein:

Figure 1 is a longitudinal sectional view through a portion of a rock drill showing the lubricator in place therein. Fig. 2 is a 5 cross sectional view on the line 2—2 of Fig. 1 and on an enlarged scale. Fig. 3 is a detail sectional view at right angles to Fig. 2 and on equal scale therewith.

Similar reference numerals designate corresponding parts in all the figures of the drawings.

In the embodiment illustrated, a cylinder member is employed including a body or barrel 4 and a rear head 5. Operating in the barrel is a reciprocating piston 6 having an internal constant pressure chamber 7 arranged to receive a supply of fluid under pressure, which is distributed for the purpose of actuating the piston and for cleansing the drill hole. To this end, ports 8, lead from the constant pressure chamber through the piston walls, and coöperate with suitable channels and ports in the cylinder for distributing the fluid to opposite ends of the piston for the purpose of actuating

the sanie. A passageway or conduit 9 extends from the constant pressure chamber 7 longitudinally through the reduced forward portion 10 of the piston that opens through its front end, being alined with the 60 bore 11 formed in the drill bit 12. Thus a portion of the fluid under pressure will enter the bore 11 of the drill bit, and consequently be directed to the bottom of the drill hole.

65 In the present embodiment, the chuck 13 in which the drill bit 12 is placed, is rotatable and its rotation is automatically effected from the piston by suitable ratchet mechanism, shown generally and designated 70 14. This mechanism is substantially the same as that shown in my copending application, Serial No. 875,465, filed Dec. 4, 1914, and it is believed requires no particular description. Inasmuch as this rotating mechanism is located at some distance from the body of the tool and is quite isolated, and furthermore inasmuch as it is necessary to keep the parts well lubricated, in view of their constant and rapid motion, means is 75 employed for effecting the lubrication of the rotating mechanism and chuck, as well as the piston and other parts. To this end, there is interposed between the barrel 4 and rear head 5 a lubricant reservoir designated 80 generally 15, said reservoir having inner and outer end walls 16 and 17, an outer tubular wall 18 and an inner tubular wall 19 thereby forming an inclosed lubricant holding chamber 20, to which access can be 85 gained by a filling port 21 closed by a removable plug 22. Motive fluid from any suitable source is supplied to the tool by a conduit (not shown) which is adapted to be connected to a coupling 23 secured to the 90 rear head 5, and extending from the rear head through the inner tubular wall 19 into the constant pressure chamber 7 of the piston, is a supply tube 24 that delivers the 95 fluid to the said constant pressure chamber. 100

The inner tubular wall 19 of the reservoir is tapered in character, its rear portion being thicker than its front portion, and formed therein is a passageway 25 opening, as shown at 26, into the outer portion of 105 the chamber 20 and also communicating with an annular groove 27 formed in the inner face of the tubular wall 19 around the tube 24. A port 28, opening through the 110 tube 24, affords communication between the

groove 27 and the bore of said tube. A wick or screen 29 is preferably placed in the passageway 25, being held in place by a plug 30. In the diametrically opposite portion of the inner tubular wall 19 of the reservoir is threaded a conduit 31 which extends through said wall into the outer portion of the chamber 20. The projecting portion of this conduit is filled with wicking or screen material 32. The said conduit thus has communication with the outer portion of the chamber 20 and opens through the rear portion of the wall 19, where it is in communication with a port 33 formed in the tube 24 on the opposite side to the port 28 and in rear of the same.

The principle upon which the lubricator works is the rise and fall in the fluid pressure in the constant pressure chamber 7 and the supply conduit immediately adjacent thereto, due to the consumption of the fluid by the rapid forward and backward movement of the hammer piston. This rise and fall of pressure causes a pulsation of the fluid through the two channels of communication between the tube 24 and the lubricant reservoir chamber 20. The pulsation of the fluid into and out of the reservoir through the channels tends to vaporize the oil and takes it out in the form of vapor which furnishes a uniform supply of oil to every part of the drill. The rotating mechanism is as thoroughly lubricated as is the piston, which is not the case if oil is introduced into the machine in liquid form. Furthermore, with the arrangement of the said channels of communication, it is not possible to submerge the outer ends of the channels simultaneously as one or the other will be above the oil level according to the position of the drill. This arrangement is necessary for the reason that if both openings 26 and 33 are simultaneously submerged when the motive fluid is turned off of the drill and the pressure therein falls to atmospheric pressure, the lubricant would be forced out of the chamber by the fluid expanding therein down to said atmospheric pressure. By having one of the outlets always above the level, the expanding fluid can escape therethrough and will not drive the lubricant out.

From the foregoing, it is thought that the construction, operation and many advantages of the herein described invention will be apparent to those skilled in the art, without further description, and it will be understood that various changes in the size, shape, proportion and minor details of construction may be resorted to without departing from the spirit or sacrificing any of the advantages of the invention.

Having thus fully described my invention, what I claim as new, and desire to secure by Letters Patent, is:—

65 1. In apparatus of the character set forth,

the combination with a cylinder member and a piston operating therein, said cylinder member including a barrel and a rear head, of a lubricant reservoir clamped between the barrel and rear head and having a lubricant holding chamber, means for delivering motive fluid through the chamber to the cylinder member, and means for delivering lubricant to the delivering means.

2. In apparatus of the character set forth, the combination with a cylinder member and a piston operating therein, said cylinder member including a barrel and a rear head, of a lubricant reservoir clamped between the barrel and rear head, a supply tube for fluid under pressure extending through the lubricant reservoir and having a slidable engagement with the piston, and means for supplying lubricant from the reservoir to the tube.

3. In apparatus of the character set forth, the combination with a cylinder member and a piston operating therein, said cylinder member including a barrel and a rear head, of a lubricant reservoir clamped between the barrel and the rear head, a supply tube for fluid under pressure extending through the lubricant reservoir and having a slidable engagement with the piston, and conduits from the reservoir communicating with the tube at different points longitudinally along the same.

4. In apparatus of the character set forth, the combination with a cylinder member and a piston operating therein, said cylinder member including a barrel and a rear head, of a lubricant reservoir clamped between the barrel and rear head, a supply tube for fluid under pressure extending through the lubricant reservoir and having a slidable engagement with the piston, and conduits communicating with the reservoir at different points and with the tube at different points longitudinally along the same.

5. In apparatus of the character set forth, the combination with a cylinder member and a piston operating therein and having a conduit extending therethrough and opening through its front end for the conveyance of a cleansing fluid to a drill bit operated on by the piston of a rotatable drill holding chuck associated with said front end, and means for delivering lubricant to said conduit to be conveyed by the cleansing fluid to the chuck.

6. In apparatus of the character set forth, the combination with a cylinder member and a piston operating therein and having a conduit extending therethrough and opening through its front end for the conveyance of a cleansing fluid to drill a bit operated on by the piston, of a rotatable drill holding chuck associated with said front end, mechanism engaging the front end of the piston and the chuck for effecting the

rotation of the latter from the former, and means for delivering lubricant to said conduit and causing it to be vaporized and conveyed in vaporized condition by the cleansing fluid to the chuck and rotating means.

7. In apparatus of the character set forth, the combination with a cylinder member and a piston operating therein, said piston having an internal constant pressure chamber, means for distributing fluid therefrom to the cylinder member to operate the piston, and a passageway leading through the front end of the piston for conveying cleansing fluid to a drill bit operated on by said piston, of a tube communicating with the constant pressure chamber and having a sliding engagement with the piston for supplying fluid under pressure to the chamber, and means for delivering lubricant to the tube 20 and causing the same to be vaporized.

8. In apparatus of the character set forth, the combination with a cylinder member and a piston operating therein, of a lubricant reservoir having a lubricant holding chamber, means for supplying fluid under pressure to the cylinder member to actuate the piston, and means for causing the delivery of lubricant from the chamber to the cylinder member, said means including passageways communicating with the fluid supply means at different points and with the outer portion of the lubricant holding chamber at different points.

9. In apparatus of the character set forth, the combination with a cylinder member and a piston operating therein, said cylinder member including a barrel and a rear head, of a lubricant reservoir interposed between the barrel and head, a supply tube for fluid 40 under pressure passing through the reservoir and slidably entering the piston, and passageways leading from the reservoir into the tube.

10. In apparatus of the character set forth, the combination with a cylinder mem-

ber and a piston operating therein, said cylinder member including a barrel and a rear head, of a lubricant reservoir interposed between the barrel and head and having inner and outer tubular walls, a supply 50 tube for fluid under pressure passing through the inner tubular wall into the cylinder member, and passageways leading from the reservoir into the tube.

11. In apparatus of the character set forth, the combination with a cylinder member and a piston operating therein, said cylinder member including a barrel and a rear head, of a lubricant reservoir interposed between the barrel and the head and having 60 inner and outer tubular walls, a supply tube for fluid under pressure passing through the inner tubular wall into the cylinder member, and passageways leading from the reservoir into the tube, said passageways communicating with the tube at different points longitudinally thereof.

12. In apparatus of the character set forth, the combination with a cylinder member including a barrel and a rear head, and a piston operating in the cylinder member and having an internal constant pressure chamber, a lubricant reservoir interposed between the barrel and rear head and having inner and outer walls, a supply tube for 75 fluid under pressure extending through the inner wall into the constant pressure chamber of the piston, and passageways communicating with the tube at different points longitudinally of the same and communicating with opposite outer portions of the lubricant reservoir.

In testimony whereof I have hereunto set my hand in presence of two subscribing witnesses.

OMAR E. CLARK.
